[57] CLAIM

The ornamental design for a vehicle-supported shelter, as shown and described.

DESCRIPTION

FIG. 1 is a perspective view of a vehicle-supported shelter embodying our new design, it being understood that the broken lines depicting a vehicle are for illustrative purposes only;

FIG. 2 is an enlarged perspective view thereof;

FIG. 3 is a rear elevational view of FIG. 2;

FIG. 4 is a front elevational view of FIG. 2;

FIG. 5 is a top plan view of FIG. 2; and,

FIG. 6 is a side elevational view FIG. 2.
